(57) **CLAIM**

The ornamental design for a "glove with index finger grip and impact guard," as shown and described.

DESCRIPTION

FIG. 1 is a perspective view of a glove with index finger grip and impact guard, showing my new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings on the design illustrate features of the article to which the design is applied that form no part of the claim. The broken-line oval shown in FIG. 7 that defines the bounds of the claimed design forms no part thereof.
